UNITED STATES PATENT OFFICE.

WILLIAM H. GODFREY, OF SOMERVILLE, MASSACHUSETTS.

WEATHER-STRIP ATTACHMENT.

1,141,390.

Specification of Letters Patent. Patented June 1, 1915.

Application filed September 15, 1913. Serial No. 789,772.

To all whom it may concern:

Be it known that I, WILLIAM H. GODFREY, a citizen of the United States, residing at Somerville, county of Middlesex, State of Massachusetts, have invented an Improvement in Weather-Strip Attachments, of which the following description, in connection with the accompanying drawing, is a specification, like characters on the drawing 10 representing like parts.

This invention relates to improvements in weather strip attachments especially adapted for sealing the bottom of doors, although the same is equally applicable to other uses.

15 The object of this invention is to improve and simplify the construction of weather strip attachments in which the weather strips are adapted to be withdrawn into the edge of the door or other device to 20 which they are applied when the same is open and to be projected downwardly therefrom into engagement with the floor or sill when the door is closed. In devices of this character the weather strip is guided at its 25 ends and is moved laterally by means of links, toggles or other connections which are secured to and operated by an actuator. In most instances the actuator is located 30 within a casing and has a portion which projects beyond the edge of the door and is adapted to engage with the door jamb as the door is closed. Such engagement with the door jamb serves to move the actuator longitudinally and to thereby act upon the 35 weather strip to move it laterally in the manner aforesaid.

In devices heretofore constructed the spring which operates to withdraw the actuator has been placed in various awkward 40 positions interfering with other parts or making a complicated structure, especially when the spring is placed at the end of the actuator the connecting devices cannot be properly positioned to force down the 45 extreme ends of the weather strip. In such devices also the actuator has been operated either directly or through an adjustable member secured thereto.

In accordance with my invention I recess 50 the actuator to receive a compression spring and I provide an independently supported and adjustable plunger to coöperate with the actuator to force the same forward.

55 My improved adjustable plunger is carried by the end plate and fits closely therein presenting a neat and finished appearance.

By such construction the attachment is much more easily applied to the door or moving part, is capable of being made much stronger and presents a better appearance when applied.

The novel features of the invention will more fully appear from the following specification and the drawings, and will be particularly pointed out in the claims.

In the drawing; Figure 1 represents a door partly in section showing this invention as applied thereto with the door closed; Fig. 2 is a similar view of a door partly in section showing this invention with the weather strip withdrawn into the base of the door and the plunger for the actuator extending through the edge of the door ready for engagement with the door jamb, a modified form of plunger being shown. Fig. 75 3 is a vertical sectional view on lines 3—3 Fig. 1. Fig. 4 is a sectional view of a lower portion of the door showing the end of the actuator, a slide abutting the same and a relatively adjustable thrust block and Fig. 5 80 is a sectional view of the plunger on lines 5—5 Fig. 4.

This invention is adapted to be applied to any form of door and may be operated with a sliding door as well as with a hinged door. 85 In order to apply this invention to the door, the door is grooved and the weather strip attachment placed therein.

In the embodiment of the invention which is illustrated in the drawing of this application, 1 represents the door, 2 a slot in the base of the door in which the weather strip attachment is inserted. End plates 3 and 4 which are fastened to the edges of the door serve to close the groove and also to prevent longitudinal movement of the weather strip. The end plate 4 is provided with an orifice 5 through which the end of the plunger is adapted to project for engagement with the door jamb or other relatively stationary member.

The weather strip attachment comprising my invention consists of a channel shaped casing 6 U-shaped in cross section and made preferably of metal, which serves to receive 105 the weather strip when retracted and also incloses and acts as a guide for the actuator and its spring in the manner hereinafter described.

The weather strip 7 comprises a smaller 110 channel shaped frame preferably of metal adapted to slide within the main casing 6,

a resilient member 8 such as felt being firmly clamped between the edges of the channel shaped member 7 and adapted to press firmly upon the floor or the sill when the weather strip is projected upon the closing of the door. The actuator as shown in this embodiment may comprise a longitudinal member 9, preferably wood, rectangular in cross section, which fits within the base of the channel shaped casing. The casing thus constitutes a guide which embraces three sides of the actuator. Pins 10, and 11 which pass through the sides of the casing adjacent to the remaining side of the actuator serve to confine it from lateral movement while permitting free longitudinal movement.

The pins 10 and 11 preferably engage in recesses 12 and 13 in the actuator which recesses are of just the necessary length to permit the desired movement of the actuator. The actuator may however be made sufficiently narrow so that these pins may be placed below it without interfering with the weather strip.

The upper edge of the actuator is provided with a longitudinally extending recess 14 which is adapted to receive a helical compression spring 15. A pin 16 passed through the casing serves as an abutment for one end of the spring while the other end thereof abuts against the shoulder 17 at the other end of the recess. It will be apparent that by the construction the helical spring is securely held in place and is prevented from buckling by reason of the fact that it is wholly inclosed by the casing and actuator. Being a compression spring it cannot break loose and become inoperative.

In assembling the above construction the spring is placed in the recess in the actuator and the actuator thereupon thrust within the U-shaped casing. When in place the pin 16 is passed through the casing at the end of the spring. If, however, the pin passes through between the spirals of the spring it will serve equally well since it would merely shorten the effective length of the spring. It will thus be observed that the construction is very simple in character and very easily assembled.

I provide an adjustable plunger independently supported in the end plate 4, to engage the door jamb or other relatively stationary element and force the actuator forward. In the structure illustrated a sleeve 18 is secured to or made integral with the end plate and is positioned in alignment with the actuator 9. This sleeve is slotted as shown at 19. A slide 20 engaging the actuator at one end is mounted in this sleeve and is provided with fins 21 projecting into the slots 19 in the sleeve. The outward movement of the slide is limited by the fins

engaging the ends of the slots. The end of the actuator 22 may be reduced and shouldered to project into the slide 20 if desired. A thrust block 23 is also slidably mounted in the sleeve and is adjustably connected to the slide as by a screw threaded connection such as indicated at 24.

In order to impart lateral movement to the weather strip from the longitudinal movement of the actuator links 25 or other suitable connections well known in the art are provided. In the constructions heretofore named the connections between the actuator and the weather strip have been placed at such distances from the end of the weather strip that it could warp up at its ends and leave a crack sufficient to admit considerable amount of air. In devices constructed in accordance with my invention in which the spring for the actuator is seated in a recess in the back thereof ample provision is made for placing the links or other means connecting the actuator and the weather strip adjacent to the ends thereof so that upon the forward movement of the actuator the ends of the weather strip will be projected firmly against the door sill.

In the form of my invention illustrated in Fig. 2 the actuator is formed with an integrally reduced end to provide a plunger 26 which is adapted to project through the orifice into the end plate in the manner aforesaid. In the device in the form of my invention illustrated in Figs. 1 and 4 the links 25 connecting the actuator with the weather strip are likewise closely adjacent to the end of the weather strip and actuator since the space required for the sleeve and its plunger occupy but about two inches which is relatively small compared with the length of the weather strip.

By reason of the adjustable plunger being thus independently mounted, not only is the device more easily applied to the door but the possibility of breaking of a projecting portion which cannot be easily replaced by substitution of a new part is avoided.

It will be obvious to one skilled in the art that various changes may be made within the spirit of the invention as defined in the claim.

Having described my invention what I claim as new and desire to secure by Letters Patent is:—

In a weather strip, a metallic casing therefor U-shaped in cross section, a one piece actuator longitudinally slidably mounted in said casing adjacent to the base thereof, a recess in the top of said actuator intermediate of its ends and adjacent to said base, a compression spring in said recess inclosed within the walls of said casing and the wall of the recess of said actuator whereby the spring will be prevented from buckling, a pin secured in the walls of the

metallic casing passing through said recess adjacent the end of the spring, and means connecting said actuator to said weather strip adjacent the ends thereof and adapted to project said weather strip laterally as the actuator is moved longitudinally against the force of the spring.

In testimony whereof, I have signed my name to this specification, in the presence of two subscribing witnesses.

WILLIAM H. GODFREY.
